UNITED STATES PATENT OFFICE.

SYLVESTER VOORHIES, OF ENDERLIN, NORTH DAKOTA.

TELEGRAPH-SOUNDER CIRCUITS.

1,296,142.

Specification of Letters Patent.

Patented Mar. 4, 1919.

Application filed March 11, 1918. Serial No. 221,841.

To all whom it may concern:

Be it known that I, SYLVESTER VOORHIES, a citizen of the United States, and a resident of Enderlin, in the county of Ransom 5 and State of North Dakota, have invented certain new and useful Improvements in Telegraph-Sounder Circuits, of which the following is a specification.

One object of my invention is to provide 10 means for operating a telegraph sounder in connection with a storage battery charged from the line circuit.

Another object of my invention is to provide 15 a telegraph sounder having two windings on its actuating coils, one of which is energized from a local circuit and the other of which is energized from the main line circuit.

With these and incidental objects in view 20 the invention consists of certain novel features of construction and combination of parts, the essential elements of which are hereinafter described with reference to the drawing which accompanies and forms a 25 part of this specification.

In the drawing Figure 1 is a side elevation of a common type of sounder having means for applying my invention thereto, and Fig. 2 is a schematic circuit drawing 30 showing the connections of sounder, relay, battery, etc.

In the sounder shown in Fig. 1 the sounder bar 1, of ordinary construction, carries at its rear end a flexible spring 2 adapted 35 to make contact with a screw 3 carried by the guard post 4 mounted with the rest of the sounder on the insulated base 5.

The guard post is brought around into a horse shoe bend as at 6 to serve as a guard 40 for the flexible spring 2, and each one of the pair of coils 7 and the contact connections are brought out to suitable binding posts carried on the insulating base 5.

Referring to the schematic circuit shown 45 in Fig. 2, the west line will come in at 8 and the east line at 9, the battery connections being such that the main line current will charge the storage battery 10 while the main line circuit is closed, this charging 50 circuit being as follows:

From the point 8, wire 11, relay coil 12, wire 13, main line sounder coils 14, wire 15, storage battery 10, to the east going line at 9.

55 When the main line circuit is opened by an operator taking control of the line, there-

after by the closing of his key, he will close the main line circuit just traced, and in addition will close the following circuit:

Storage battery 10, wires 16, 17, contact 60 18, wire 19, local sounder coils 25, contact 26, wires 27 and 28, to the other side of the storage battery 10.

The storage battery will then actuate the sounder bar through the coils 25 strongly, 65 so as to give the proper sound to the instrument, and when the sounder bar has moved a certain distance, the contact 26 will be opened, permitting the sounder bar to be held down, or the remainder of its travel 70 downwardly to be effected by the main line coils 14 in the main line circuit heretofore traced.

The relay will, of course, follow the key 75 in the usual manner, and the sounder bar will repeat the signals in the usual way, the local coils 25 and the storage battery 10 furnishing the necessary energy for giving the sounder bar the proper sounding blow.

An additional contact 29 is carried by the 80 relay, and through wires 17 and 15 on the one side and wires 30 and 13 on the other side, short circuits the main line sounder coils 14 when the contact is closed.

This is to prevent the actuation of the main line sounder coils 14 becoming sluggish or non-responsive when there is considerable leakage on the main line.

The relay is, of course, as usual, adjustable 90 to meet just such conditions, but it is not thought advantageous to make the sounder adjustable and hence the main line coils are short-circuited by the back contact of the relay for the purpose stated.

While I have described my invention and 95 illustrated it in one particular design, I do not wish it understood that I limit myself to this construction, as it is evident that the application of the invention may be varied 100 in many ways within the scope of the following claims.

Claims:

1. In a telegraph sounder circuit the combination of a sounder having a low resistance winding and a high resistance main line winding, an armature controllable by said windings, a contact controlled by said armature, a main line relay having a contact, a storage battery, circuit connecting 110 means for including said storage battery in series with a main line circuit, and circuit

connections including said two contacts for connecting said storage battery across said low resistance coil.

2. In a telegraph sounder circuit the combination, with a main line circuit having a direct current flow, of a storage battery connected in opposition to said current flow, a relay winding in series with said storage battery, a sounder having a main line winding and a local winding, said main line winding being in series with said relay winding and said storage battery, a circuit closing contact and a circuit opening contact in series with said storage battery and said local winding whereby, on the actuation of said circuit closing contact, said storage battery is connected across said local coils, and upon the later actuation of said circuit opening contact said storage battery is cut off from said local coils.

3. In a relay sounder circuit the combination of a telegraph sounder, a storage battery and a relay, a circuit for connecting said storage battery into charging relation with a main line circuit, and cooperating circuits for utilizing said storage battery to partially operate said sounder and also to utilize the main line circuit connected therewith for partially operating said main line sounder.

4. A telegraph sounder circuit comprising a sounder, having two or more coils, a storage battery, a main line circuit having a

battery connection for charging said storage battery normally, circuit changing means 35 for switching said battery from a charging circuit, including the main line circuit, to a discharging circuit including a coil of said sounder, and means for short-circuiting one of said sounder coils to prevent line current 40 leakage through the convolutions thereof.

5. In a telegraph sounder circuit comprising a sounder having a local coil and a main line coil, a storage battery, a main line circuit having a battery connection for normally charging said storage battery, a relay, circuit connections controllable by said relay for switching said storage battery from a charging circuit, including the main line circuit, to a discharging circuit including a coil of said sounder, and a circuit controllable by said relay for short-circuiting said main line coil of said sounder to prevent line current leakage through the convolutions thereof.

6. In a telegraph sounder circuit the combination of a sounder having a local coil and a main line coil, a relay, a local battery, a circuit controlled by said relay for actuating said local coil by said local battery, and a circuit controlled by said relay for short-circuiting said main line coils to prevent line current leakage through the convolutions thereof.

SYLVESTER VOORHIES.
